UNITED STATES PATENT OFFICE.

JOHN R. LOMAS, OF WEST HAVEN, CONNECTICUT.

COMBINED CLOTHES-DRIER AND FIRE-ESCAPE.

SPECIFICATION forming part of Letters Patent No. 573,673, dated December 22, 1896.

Application filed May 4, 1896. Serial No. 590,078. (No model.)

To all whom it may concern:

Be it known that I, JOHN R. LOMAS, of West Haven, in the county of New Haven and State of Connecticut, have invented a new 5 Improvement in a Combined Clothes-Drier and Fire-Escape; and I do hereby declare the following, when taken in connection with the accompanying drawings and the letters of reference marked thereon, to be a full, clear, 10 and exact description of the same, and which said drawings constitute part of this specification, and represent, in—

Figure 1, a view in side elevation of one form which my improved clothes-drier and 15 fire-escape may assume; Fig. 2, a detached sectional view showing the means for fastening one of the clothes-driers against rotation; Fig. 3, a plan view of one of the clothes-driers; Fig. 4, a broken view in side elevation, showing 20 a modified form of the revolving clothes-drier, the inclined ladder being made independent thereof; Fig. 5, a plan view of the construction shown in the preceding figure, but with the clothes-drier removed to better 25 show the independently-constructed inclined ladder.

My invention relates to an improved combined clothes-drier and fire-escape, the object 30 being to provide a simple, strong, and convenient apparatus combining the two functions indicated and particularly designed to be used in connection with tenement-houses so high as to preclude their provision with the clothes-driers ordinarily employed.

With these ends in view my invention consists in certain details of construction and 35 combinations of parts as will be hereinafter described, and pointed out in the claims.

Although it will be understood that my improved apparatus is adapted to be applied to 40 buildings many stories in height, it will be obvious that its principle will be illustrated by merely showing it applied to a building of two stories.

In carrying out my invention as herein 45 shown I employ a perpendicular shaft A, arranged at a suitable distance, say five feet, from the building B, although the distance may be varied as desired. By preference the 50 shaft A will be made hollow and constitute a stand-pipe, its lower end being connected with any suitable source of water-supply. If

used as a stand-pipe, it will be provided with suitable hose connections A' A', of which there will be one for each story of the building. These connections will provide for the attachment of the hose for leading water into the stories of the building from the shaft and avoid the use of such long lengths of hose as would be required if the water were brought 55 from the street-level to the various stories of the building. As herein shown, the shaft is supported and stayed by means of horizontal stays or braces A², connecting it with the building, but it is not necessary that these 60 braces should have the particular form shown. Upon the shaft I mount a series of revolving clothes-driers, of which there may be one for each story of the building, although that is not imperative. 70

The revolving clothes-drier shown in Figs. 1 and 3 is octagonal in general form and tapers at its lower end. It is composed of radially-arranged frame-pieces C, connected at their inner ends with hub-like frame-plates 75 C', mounted upon the shaft so as to rotate freely thereupon. The outer portions of these radial frame-pieces are united by means of clothes-lines C², which may be made of wire or metallic rods, and which, in addition to 80 their function of providing for hanging out clothes, serve also to maintain the frame-pieces in their proper positions. Only seven sides of the octagon are provided with clothes-lines, one side being left sufficiently open to 85 allow a passage from the building into the drier when the open side of the drier is brought into line with the window by revolving the drier. This open side of the drier is furnished with an inclined series of ladder-rungs D, 90 which are extended between two of the frame portions C and form a ladder leading downwardly toward the shaft. Near the lower end of the ladder thus formed I locate an open platform E, from which access is had to the 95 vertical ladders F, located in the center of the revolving drier and affording communication up and down through the series of driers. Preferably each revolving drier will be provided with three vertical ladders F, as 100 shown in Fig. 3, as that increases the convenience of the device, but one vertical ladder will answer the purpose of the invention.

It is designed that ordinarily the driers shall

normally be held against rotation by means of a fastening device, (shown in Fig. 2,) to consist of a pivotal bail G and adapted to be engaged with retaining-pins G', located in the 5 sill of the window of the story which has the drier adjacent to it; but the particular means employed for fastening the revolving drier, if any means are employed, may be variously modified. The drier is supported upon the 10 shaft, as shown in Fig. 1, by means of a collar H, rigidly secured thereto and having the lower hub-like frame-plate C' resting upon it.

As shown in Fig. 1, the upper story of the 15 building is not provided with a revolving drier, but with a skeleton fire-escape, which need not be described in detail more than to say that it comprises an inclined ladder I and also comprises vertical ladders I', of which only one is shown. In case the inclined ladder leads to the roof it would not be necessary that the fire-escape should be provided with the ladders I'.

In the modified form of my device shown 20 in Figs. 4 and 5 the revolving clothes-drier J does not include the inclined ladder K, leading from the building to the shaft, but the said ladder is made independent of the drier and secured directly to the building at its upper end and at its lower end to the shaft 25 30 A through the medium of the brace L, which stays and supports the shaft; but in this modified construction the revolving drier must be provided with one or more of the vertical ladders F.

In view of the modifications shown and suggested, it is apparent that in carrying out my 35 invention I may make changes and alterations in the construction illustrated and described, and I would therefore have it understood that 40 I do not limit myself thereto, but hold myself at liberty to make such changes as fairly fall within the spirit and scope of my invention.

Having fully described my invention, what I claim as new, and desire to secure by Letters 45 Patent, is—

1. A revolving clothes-drier comprising an inclined ladder leading from a point at or near its outer edge to a point near its center.
2. A revolving clothes-drier comprising an

inclined ladder leading from a point at or near 50 its outer edge to a point near its center, and also comprising a centrally-arranged vertical ladder extending from its upper to its lower end.

3. A revolving polygonal clothes-drier having 55 its several sides occupied by suitable clothes-lines except one side, where they are omitted, and which is left open to form a passage-way for an inclined ladder incorporated in and leading from a point at or near the 60 edge of the drier to a point near the center thereof, and the said drier also comprising a centrally-arranged vertical ladder extending from its upper to its lower end.

4. The combination with a perpendicular 65 shaft, of a series of revolving clothes-driers located one above the other on the said shaft, and each containing a centrally-arranged ladder extending from its upper to its lower end, whereby communication between the several 70 driers is provided for, and one or more inclined ladders extending between the shaft and the building adjacent to which it is placed, and forming communication through the 75 driers between the building and the vertical ladders before mentioned.

5. The combination with a perpendicular shaft, of lateral stays for connecting the same with the building adjacent to which the shaft is placed, a plurality of revolving clothes-driers mounted upon the shaft, one above the other and between the said stays, and each furnished with a centrally-arranged vertical ladder extending from its upper to its lower end, whereby access between the several 85 driers is provided for, and each drier being also provided with an inclined ladder extending from a point at or near its outer edge to a point near its center, whereby communication between the building and the vertical 90 ladders before mentioned is provided for.

In testimony whereof I have signed this specification in the presence of two subscribing witnesses.

JOHN R. LOMAS.
